UNITED STATES PATENT OFFICE.

ISAAC S. DAULEY, OF ONEONTA, NEW YORK.

REINFORCED-CONCRETE TOMB AND MEMORIAL.

1,195,787.

Specification of Letters Patent. Patented Aug. 22, 1916.

Application filed February 7, 1916. Serial No. 76,701.

To all whom it may concern:

Be it known that I, ISAAC S. DAULEY, a citizen of the United States, and a resident of Oneonta, in the county of Otsego and 5 State of New York, have invented certain new and useful Improvements in Reinforced-Concrete Tombs and Memorials, of which the following is a specification.

My invention relates to the interment of 10 human dead, and the object thereof is to provide a combined burial and memorial means which will be enduring, sanitary, and give absolute protection to the human dead, which may be provided for before death, and 15 which will be within the means of people who are financially unable to build a durable mausoleum and memorial above ground.

It is the desire of many people to provide 20 for their place of interment after death, but this has heretofore been possible to wealthy persons only, but by means of my invention relatively poor people will be enabled to gratify their desire to prepare their permanent resting place long before death, and 25 also be enabled to prepare the resting places for all the members of a family many years before needed, in the full confidence that the tomb will be in perfect condition for the reception of the remains of the individual 30 for whom it is intended, when death occurs.

My invention is fully described in the following specification, of which the accompanying drawings form a part, in which like characters refer to like parts in each of the 35 views, and in which:

Figure 1 is a view of a set of three tombs constructed in accordance with my invention, one being ready for the reception of the remains, another having the burial vault 40 therein, and the third being sealed and provided with the memorial tablet; Fig. 2 is a section taken on the line 2—2 of Fig. 3, and showing means for preventing the entrance of water into the tomb; Fig. 3 is a longitudinal section taken through the intermediate tomb shown in Fig. 1, but with the memorial tablet in place, awaiting the necessity for use; and Fig. 4 is a transverse section taken through a set of three tombs, the two 45 of which on the left hand are awaiting the necessity for use, and the one on the right hand having the human remains therein, the two on the right hand being partly broken away to show the structural details of the 50 vaults.

Referring to the drawings, 5 represents an excavation in the ground of a size adapted for one or a plurality of the tombs, three being shown in the drawings, and indicated by the reference characters 6, 7 and 8, these 60 having their floors and walls formed of reinforced concrete 9 and being provided, when constructed, with tablets 10, 11 and 12, respectively, of marble, granite, bronze, or any suitable equivalent, definitely positioned by bronze dowel pins, these not being shown as they are an old and well known expedient.

When a plurality of tombs are provided in one excavation I provide a channel 13 70 along the top of the wall or walls therebetween to carry off water but, if one or more tombs are provided, I surround the top of each one with a channel 14 having a drain 15 led downwardly to a mass of broken stone 75 16 to insure a proper drainage of the channel 14, the function of the channel 14 being to intercept water which might ooze between the tomb and the tablet during the period intervening between construction and use of 80 the tomb, and thereby insuring absence of moisture within the tomb when its use is required.

At 17 is shown a burial vault formed of reinforced concrete, as for instance the type 85 known as the "Norwalk reinforced concrete vault" and within one of which is shown a burial casket 18 of any type, neither the particular vault nor the casket forming a part of my invention except in so far as the provision of a receiving tomb is provided therefor long before the contemplated necessity of use, and the manner of sealing the casket and vault within the tomb for all time because of the homogeneous mass formed by 95 the concrete tomb, the concrete vault, and the concrete filler 19 after the tomb has been sealed, as shown at the right hand of Fig. 4.

After the concrete filler 19 has been placed 100 within the tomb the tablet is placed thereover and the desired memorial matter may then be inscribed thereon or, if partially inscribed previously, may then be completed, and a resting place for the human remains 105 results which is permanent and, because of its being beneath the surface of the earth, is proof against the action of the elements for all time.

From the foregoing it will be seen that a 110

person may provide a resting place for one or more people long before any need therefor exists and when he may be better able financially to meet the expense thereof than 5 when the need therefor occurs, thereby gratifying his desires in this respect, removing all doubts from the minds of the contemplated occupants as to the place of burial of each, and reducing the actual burial 10 cost of each when death occurs, while at the same time giving assurance of a permanent tomb at a relatively low cost.

One of the principal features of the invention resides in the provision of means for 15 preventing the entrance of water into the tomb while awaiting the death of its contemplated occupant, these means consisting, in the form shown, of the drainage channels and passages, but I do not desire to limit 20 myself to any specific form thereof as many modifications over the form shown and described may be conceived and still be within the spirit of the invention, and the scope of the appended claims.

25 As shown at 20, each of the ledger stones or tablets 10, 11 and 12 may be grooved on its undersurface complementary to the drainage channels 14, whereby any water which may trickle through beneath the rim of the 30 tablets will be obstructed in its flow so as to be sure to find its way into the channels 14 and not be conveyed into the interior of the vault chambers.

Having fully described my invention,

what I claim as new, and desire to secure by 35 Letters Patent, is:—

1. A resting place for human dead comprising a tomb formed of concrete providing a chamber for the reception of a burial casket or the like, said tomb structure being 40 provided around its upper edge with a drainage channel, and a memorial tablet fitted and supported upon said upper edge, said tablet being provided along its under surface with a groove complementary to said 45 channel whereby water tending to enter the chamber aforesaid will be received and directed into said channel.

2. A resting place for human dead comprising a tomb formed of permanent material providing a chamber for the reception of a burial casket or the like, said tomb being provided around and in its upper edge with a drainage channel, and a memorial tablet fitted and supported upon said upper 50 edge and covering said channel, said tablet being provided along that portion thereof which coöperates with the upper edge of the tomb with means whereby water tending to enter the chamber aforesaid will be received and directed into said channel.

In testimony whereof I have signed my name to this specification in the presence of two subscribing witnesses.

ISAAC S. DAULEY.
